UNITED STATES PATENT OFFICE.

CARL CHRISTIAN SONNE, OF SHANGHAI, CHINA.

TELEPHONE SWITCH-BOARD.

SPECIFICATION forming part of Letters Patent No. 328,618, dated October 20, 1885.

Application filed December 22, 1884. Serial No. 150,900. (No model.)

To all whom it may concern:

Be it known that I, CARL CHRISTIAN SONNE, a citizen of Denmark, and a resident of Shanghai, China, have invented a certain new and useful Improvement in Telephone Switch-Boards, of which the following is a specification.

The object of my invention is to provide a switch-board for telephone-exchange systems, whereby, first, the annunciator-drops may themselves automatically connect the subscriber's line to earth or to the central office electric generator or to the telephonic instrument; second, the connecting contact-plug in which the subscriber's line ends may automatically connect the subscriber's line to earth when not in use; third, the switch-board may be divided up into sections in case the number of subscribers is unusually large.

20 The invention consists in providing means for accomplishing in one switch-board these three objects, and will be better comprehended by a description in connection with the accompanying drawings.

25 Figure 1 represents a partial cross-sectional view, and partially in diagram, of the switch-board, and shows the general arrangement and shapes of the various parts. Fig. 2 shows a modification of the annunciator-drops. Fig. 3 represents the face of the annunciator-drop, while Fig. 4 represents the idea of connecting or dividing the sections of the switch-board.

Like letters and figures of reference refer 35 to like parts.

A line made of alternate long and short dashes or marks, except in Fig. 4, (in that figure the wires themselves are shown,) represents the electric circuit. Lines made of 40 successive short dashes represent movable parts in a different relative position. Irregular and continuous lines represent that a portion of the object has been omitted, as such omitted portions were not necessary to assist 45 in the description of the invention.

All unnecessary parts and details of construction are omitted for the purpose of preventing confusion.

The parts of the drawings not referred to 50 have nothing to do with my invention.

The annunciator-drops and construction consist of the electro-magnets A, lever B situated beneath the armature-lever B, pivoted upon the support E, and counterbalanced by the weight C, and adjusted in its degree of 55 swing by the screw D, the plate F on which rest the electro-magnets and which support the annunciator-drop G free to swing through an arc, so that at its extreme positions it will come into electrical contact with the springs 60 H and I, insulated from each other by being attached to the insulating substance Q.

The connecting or contact plug and surroundings consist of the plug M, fitting in an insulating-socket, R, of hard rubber or equivalent, and capable of being removed at pleasure from the said socket. The plug is metal, and is metallically connected with the flexible conductor O, and is held in place and in contact with the metal plate N by the weight 65 70 P, thus causing a complete circuit from 3 to 4 when the plug is in the socket.

The springs I (shown in front view in Fig. 4 and by one spring in side view in Fig. 1) are metallically connected in pairs, triplets, or in 75 any number, and these several collections may themselves be connected by the switches S. The switch for connecting one or more of these sets of springs with the push-button J (see Fig. 1) is shown in the lower part of Fig. 4. 80

The important parts of my switch-board having been described, its *modus operandi* will next be in order. The subscriber's call-current 85 passes through the electro-magnet A of the annunciator and through the flexible conductor into the plug M. This plug, which is kept upright by the weight underneath, makes by its lower end contact with a metallic piece, N, which is again connected to the body of the annunciator-drop G. Behind G is arranged 90 a metallic spring, H, against which G rests when in its natural position, and with which it makes electrical contact. All the springs H are connected directly to earth L, either separately or preferably being made in groups of 95 three or four, as shown in Fig. 4. In this way the circuit is completed. When a call arrives and the drop G falls down it makes contact with a spring, I, which is in connection with the central-office telephone K, or by means of 100

the push-button or key J with the electric generator T. The operator has consequently nothing to do but press down J and reply by a ring and then speak after having released J, 5 and need not touch the connecting-plug till he has ascertained the subscriber's wish. After having connected the parties he resets the drops, which may again serve to indicate when the subscribers "ring off." Immediately the 10 plug M is released it returns to its normal position, making connection with N. In this way at least two manipulations are avoided at each call. Supposing the springs I to be connected together in groups, when two or more 15 drops fall at the same time they connect several lines to the operator's telephone at once. The inconvenience of this may be avoided by the operator either replacing the drops all but the one he wishes to reply to first, or else 20 lift up the plugs M (only one is shown) of those lines that are to wait, a little way from N and thus insulating the wires until he is ready to speak to the waiting subscribers. Practically this answers very well on a switch-board up 25 to fifty lines, or when the exchange is not very busy. (I have tried it on a fifty-line switch-board.) In case, however, that calls are so frequent that this causes inconvenience, the system of springs I may be arranged in groups 30 of any convenient number, as shown in Fig. 4. Each group is then connected to a contact in the switch, (shown in Fig. 4,) the body of which is connected to the telephone K. The body of the key or switch may rotate on a 35 pivot, V, arranged to stop readily over any of the contact-pieces a. Of course the system may be attached to any form of annunciator switch-board and any convenient mode for making the connections respectively between 40 the drop and earth and telephone. Fig. 2 gives an example of another method, where the frame W of the annunciator is grounded by circuit 6, and the drop G at its lower end is made in the form of a cam, so as to connect 45 to a short spring fastened to the plate X (and does not touch W) when in its normal posi-

tion, while the stop against which G falls connects to the push-button J. This arrangement is also applicable to switch-boards worked with loose plugs. Here the subscriber's strip is 50 normally connected to the contact-piece N by the loose plug just as it is connected to the earth-strip.

I claim—

1. In a telephone switch-board, the combination of the annunciator-drop G, adapted to be held by the armature-lever B so as to make electrical contact with the spring H, the spring I, located in a position to make electrical contact with the said drop G when the latter is 60 allowed to fall by the lever B being at any time attached by the electro-magnets A, and the push-button J, which directs, according to its adjusted position, the current either to the battery F or to the telephone K, substantially 65 as described.

2. In a telephone switch-board, the combination of the adjustable plug M, fitting in or removable from the socket R and electrically connected to the conductor O, leading to the 70 subscriber's line 1, and the plate N, connected electrically with the conductor 4, which connects with the earth or with the telephone or battery, according to the position of the annunciator-lever G and push-button J, substantially 75 as and for the purposes set forth.

3. In a telephone switch-board, the combination of the groups of springs I, each located under an annunciator-lever, G, as shown, switches S, located between said groups for the 80 purpose specified, and a second switch provided with contact points a, connected each by a wire to one of said groups and arranged side by side, substantially as and for the purpose specified.

Signed at Shanghai, in China, this 6th day of August, A. D. 1884.

CARL CHRISTIAN SONNE.
